UNITED STATES PATENT OFFICE.

KENNETH DAVIS, OF ST. BENEDICT, PENNSYLVANIA, ASSIGNOR TO REMBRANDT PEALE, OF ST. BENEDICT, PENNSYLVANIA.

MEANS AND METHOD FOR TRANSPORTING LOOSE MATERIAL.

Application filed June 23, 1919. Serial No. 306,154.

To all whom it may concern:

Be it known that I, KENNETH DAVIS, a citizen of the United States, and a resident of St. Benedict, Pennsylvania, have invented ⁵ a new and useful Improvement in Means and Methods for Transporting Loose Material, of which the following is a specification.

The invention relates to a system of ¹⁰ transporting, loading, unloading, and otherwise handling loose material, the system in certain of its aspects being particularly adapted to transporting coal through and from a mine; the invention relates also to a mechanism ¹⁵ adapted for use in transporting, loading, unloading and otherwise handling loose material, such as coal, and in certain aspects thereof, to so transporting and otherwise handling coal from the mine workings and ²⁰ delivering it into railway cars or other transportation means exterior to the mine, or other source of supply of such loose material.

Objects and advantages of the invention ²⁵ will be set forth hereinafter in part, and in part will be obvious herefrom, or may be ascertained through practice with the invention; such objects and advantages being attained and realized through the instrumentalities and combinations pointed out ³⁰ in the appended claims.

The invention consists in the novel steps, system, parts, constructions, arrangements, combinations and improvements herein ³⁵ shown and described.

The accompanying drawings, herein referred to and constituting a part hereof, illustrate the practice or carrying out of the system and one embodiment of the mechanism, ⁴⁰ the same serving with the description to explain the principles of the invention.

Of the drawings:

Fig. 1 is a fragmentary top plan of one ⁴⁵ end of the transporting system, showing the mechanism for shifting transporting units from one train to the cooperating train;

Fig. 2 is a fragmentary elevation, corresponding substantially to Fig. 1, and looking at Fig. 1 from the bottom thereof as ⁵⁰ shown on the sheet;

Figs. 3, 4 and 5 are enlarged, separate de-

tails of the devices for fastening together and unfastening from each other the transportation units to unite them to and to detach them from the trains;

Fig. 6 is a transverse section, on an enlarged scale, taken on the line 6—6 of Figs. 1 and 2, and illustrates certain structural features of the transportation units;

Fig. 7 is a transverse section, on an enlarged scale, similar to Fig. 6, taken on the line 7—7 of Figs. 1 and 2;

Fig. 8 is a transverse section, on an enlarged scale, similar to Figs. 6 and 7, taken on the line 8—8 of Figs. 1 and 2;

Fig. 9 is an enlarged side elevation of the device for unloading the material from the transportation units, and showing it cooperating with one of the transportation units with the structural details of the latter ⁷⁰ omitted;

Fig. 10 is a top plan corresponding to Fig. 9;

Fig. 11 is an enlarged elevation, with parts in section, of the means for transferring the transportation units successively from the train traveling in one direction to traveling in the opposite direction;

Fig. 12 is a top plan, on a reduced scale, corresponding to Fig. 11;

Fig. 13 is an enlarged, fragmentary plan of the clutch and drive mechanism shown at the lower right hand corner of Fig. 12;

Fig. 14 is a top plan, partly diagrammatic and with parts of the mechanism omitted, ⁸⁵ showing intersecting transporting systems and the transference of the transported material from one system to the other;

Fig. 15 is a sectional elevation, likewise diagrammatic in character and with parts ⁹⁰ omitted, taken on the line 15—15 of Fig. 14, and showing the upper transporting systems in elevation;

Fig. 16 is a fragmentary diagrammatic view showing the two ends or terminals of ⁹⁵ a transporting system with the unit switching or transferring devices operating at each end or terminal to convey the successive units from the train traveling in one direction to that traveling in the other, and ¹⁰⁰ effecting the endless cycle of the system.

Fig. 17 is a diagrammatic plan of the in-

tersection of two transporting systems at the junction of a main entry with two cross entries in a mine with devices for transferring or unloading the material from the cross entry transportation system to the main entry transportation system;

Fig. 18 is a general diagrammatic view of a mine working, showing a system of transporting the coal from the rooms or other workings to the cross entries and therefrom to the main entry, and finally into railway cars without the mine; and

Fig. 19 is a detail of the control for the unit switching or transferring system.

15 The invention comprises a system operating automatically to transport loose material, such as mined coal or the like, from the face of the workings or other source of supply, into railway cars or other final conveying means, without shoveling or other usual handling or when applied to a mine, without the use of the usual mine cars, mine locomotives and the like. The system and apparatus also transports the material, such as coal, from a plurality of workings or sources of supply, as for instance from all parts of the mine simultaneously, without any source or part being held up or delayed by waiting for another. The system also provides when applied to a mine for quickly removing dislodged or "shot-down" coal from the faces of the rooms, or other workings, immediately and quickly, without any room, group of rooms or other part of the workings delaying any other part, and thereby effecting quick clearing of mined coal, and thereby leaving the faces of the workings open for the greater part of the time for undercutting and dislodging the coal, thus greatly increasing the output from a given amount or area of mine openings.

Referring now to the accompanying drawings, illustrating by way of example one embodiment of the invention, a system of two cooperating transporting trains traveling in opposite directions are provided, each train consisting of a plurality or series, and usually a very large number, of 45 uniform or standard transportation units, each such unit in succession as it reaches the end of the transportation route or path being automatically detached from the head of its train and transferred to and attached to the tail of the train traveling in the opposite direction.

The series of connected together or concatenated units occupy the entire length of the path of travel of the train, and this is 50 true of each of both parallel cooperating series, the units traveling continuously and the transference of units from the head of one train to the tail of the other going on continuously at each end. The form of 55 transportation units is such that the ma-

terial may be dumped thereinto irrespective of the position of the units, as the train presents a continuous traveling receptacle for the reception and transportation of the loose material, whether it comes regularly 70 or uniformly or intermittently. This is likewise true whether the loose material is loaded on or received from a single or from a great many sources and irrespective of whether such sources are located near together or far apart, or whether in uniform or irregular relation. Just previous to the shifting of the units as just described, they are likewise successively unloaded of the coal or other loose material being conveyed. 80 The unloading mechanism also operates without interfering with the travel of the transportation units in the train, and irrespective of the passing successively of one unit after another.

The conveyor units in the preferred embodiment comprise a bottom 1, and sides 2 and 3, with open, unobstructed ends. The conveyor units are preferably provided with an underneath frame, preferably 85 rectangularly disposed, connected together channel beams 5. The side walls of the conveyor unit, and the bottom as well, are slightly off-set or shouldered at one end, as shown at 7, in Figs. 1 and 2, so that 90 the units at their juncture will fit one within the other, the inside edges being arranged away from, that is, so as not to strike the unloading chute, as shown in Figs. 1, 2 and 9.

A suitable guide-way or track-way and progressive means for the train of transporting units are provided, and as embodied, an axle 10 is mounted in the bottom frame 5, suitable reinforcing blocks 11 and 12, fitted into frame 5, being preferably used. Upon the ends of the axle are wheels or rollers 13 and 14, which are preferably provided with transversely curved peripheries, as shown in Fig. 6, as best adapted for the transverse 100 motion of the units when transferred across from one train to another as already referred to and later described in detail. The track-ways are of any suitable form, and are shown herein as each comprising angle 110 plates 15 and 16, laid end to end and upon ties 17, much in the fashion of ordinary rails, and having vertical flanges 18 and 19 on the exterior sides to keep the units on the track and in transverse alinement.

Driving or traveling means for each train of transportation units is provided, and as embodied such means are located at one end of the train of transportation units, the train of transportation units being progressed thereby by reason of such units being attached one to the other throughout the length of the train. If desired, however, a plurality of traveling or driving devices may be provided at different points along 120 125 130

- the length of the train of transportation units. The cooperating train of transportation units which is traveling in the opposite direction may be similarly equipped, and such an arrangement is diagrammatically shown in Fig. 16. In Fig. 16 the two cooperating trains of transportation units are shown, and at each end the switching or transferring devices taking each successive transportation unit from the head of the approaching train and transferring it to and attaching it to the tail of the receding or traveling away train, and thus maintaining the endless cycle in either direction.
- In Fig. 1 an arrangement is shown wherein or whereby the train of transportation units going in one direction is controlled as to speed by the train of units traveling in the opposite direction, such controlling means being located at one end of the two trains. Such a system is adapted for use in a mine slope or other location where the units are impelled in one direction by the action of gravity, the power driven train controlling the speed of the gravity driven train, so that the transferred or switched over units can attach themselves to the tail of the gravity driven train.
- Referring more in detail to the driving means, the preferred embodiment comprises an electric motor 25, the pinion 26 of which meshes with a gear 27, which gear is fixed on a shaft 28. Fixed also on the shaft 28 is a sprocket wheel 29, over which runs a sprocket chain 30, the sprocket chain 30 at the other end thereof running over a sprocket wheel 31. Fixed upon the sprocket chain 30 are driving lugs 32, with which co-operate pins 33, which project horizontally outwardly from the bottom frames 5 of the transportation units. As the mechanism is preferably constructed, a plurality of the lugs 32 are simultaneously in engagement with a plurality of the pins 33 upon a single transportation unit, or upon two successive units, as shown in Figs. 1 and 2.
- There are preferably similar devices upon the opposite side of the transportation unit and track, and as shown in Fig. 1, shaft 28 extends across beneath the track, and fixed upon the opposite end of the shaft is a sprocket wheel 35, over which runs a sprocket chain 36, said chain at the other end thereof likewise running over a sprocket wheel 39. Lugs 39 are carried upon the chain 36, similar to the lugs 32, which lugs co-operate with pins 40, similar to the pins 33, already described.
- As already stated, such a driving mechanism may be provided at each end of each train traveling in opposite directions and co-operating together (as shown in Fig. 16), one train bringing the transportation units loaded with material in one direction, and the other train conveying the empty units in the opposite direction, the units being switched or shifted from one train to the other, at each end of the route.
- In the embodied form of means for automatically connecting together and disconnecting the transportation units in proper time relation to the switching or shifting thereof from one train to the other, (the mechanism and manner of the switching or shifting being later described), a coupling hook 45 is provided pivoted at 46 upon one transportation unit and hooking over a pin 47 upon the next adjacent transportation unit. The embodied form of disconnecting means comprises an arm 47 fixed to the hook 45, and having a projecting pin 48 adapted to engage with a tripping cam 49, mounted alongside the track, whereby the hook 45 is rocked clear of the pin 47, and the end or head transportation unit of the train is disengaged therefrom. As such unit joins or approaches the tail end of the other train, traveling in the opposite direction, a pin 50 upon the hook 45, engages with a tripping cam 51, likewise mounted alongside the track, and the hook 45 is thereby lifted, as such added unit approaches, the hook being then dropped behind the pin 47 of the transportation unit just ahead, and the approaching unit is thus fastened to the tail end of the train or series, or the bevel nose of hook 45 will serve to hook it over pin 47.
- Referring now to the mechanism in Fig. 1, whereby the speed of the train going in one direction is controlled and synchronized by the driving mechanism for the train going in the opposite direction, as for instance, the descent of the train on a mine slope would be controlled from the motive power for the ascending train, as embodied, upon the shaft 38 is fixed a pinion 54 meshing with a pinion 55 fixed on a shaft 56. Fixed also on shaft 56 is a sprocket wheel 57, over which runs a sprocket chain 58, said chain at its opposite end running also over a sprocket wheel 59. The chain 58 is provided with lugs 60, similar to the lugs 32 already described, and co-operating therewith are pins or stops 61 projecting from the side of the transportation units, which pins are similar to or identical with pins 33 already described. In this case, however, the lugs are on the forward side of the pins, considered with respect to the direction of travel of the train, and thus they restrain the speed of the transportation units, and thereby that of the train consisting of the connected together units, and maintain the speed of this train, acted on by gravity, uniform with that of the driven or ascending train, which would be the bottom train in Fig. 1. In this instance also, as embodied, there are corresponding devices on both sides of the train. For this purpose the shaft 56 extends across beneath the track and upon the opposite end

of the shaft is fixed a sprocket wheel 62, over which runs a sprocket chain 63, said chain at its opposite end running also over a sprocket wheel 64. This chain is provided 5 with lugs 65, cooperating with pins 66, projecting from the sides of the transportation units, and corresponding to or identical with pins 40.

The unloading device, as already referred 10 to, is located near one end of the path of travel of the loaded transportation train, and in accordance with certain features of the invention it operates automatically without interfering with the travel of the train 15 and requiring no workman or overseer. As embodied, it comprises a chute 70 preferably substantially rectangular in cross-section, and of a width to fit within the transportation units, the conveyor being upwardly inclined in the direction of travel of the loaded 20 train of units, and extending to a height sufficient to clear the sides of the transportation unit. The chute 70 is provided with vertical sides, 71 and 72. At a height just 25 greater than that of the transportation unit the chute is curved outwardly to one side, and preferably after passing a suitable distance laterally clear of or away from the transportation units, the chute is curved 30 downwardly to facilitate the discharge of the loose material into any suitable receptacle. The general arrangement of the present preferred embodiment of the unloading device is shown in Figs. 9 and 10.

Auxiliary unloading means cooperating 35 with the chute may be provided if desired. In Fig. 9 there is shown such means cooperating with the unloading device, as previously described, although with many materials 40 and installations, the use of this auxiliary device will be found unnecessary. As shown, it comprises a power driven endless belt conveyor 74, running over rollers 75 and 76, and having a series of flights 77 located 45 within and traveling upwardly along the chute 70 to carry the material up and along the same. The conveyor 74 may be driven in any usual or suitable manner, or by a motor in the usual manner, such devices not 50 being shown. By the mechanism just described, each unit is unloaded and cleared of the transported material as the unit travels along in its connected relationship in the transportation train, and is thus emptied 55 just previously to being switched or transferred from the head of the train to the tail of the train traveling in the opposite direction.

Referring now to the embodied form of 60 means for shifting the units successively from one train to another, there is provided just at the point of detachment of the unloaded unit, or rather of the successive units from the head of the train, a traveling means 65 running at a higher speed than the train of

units going in either direction, whereby a detached unit may be separated from its train, may be traveled or shifted transversely from alignment therewith into alignment with the other train traveling in the opposite direction and may catch up therewith and be attached thereto, that is, to the tail end of the last unit of the train as already described. By such speeding up of the detached units, they are enabled to leave one 70 train of transportation units and to arrive at the tail of the other train in time to be attached to the last unit thereof without causing any breaks in the continuity of the train.

As embodied, such means comprises two endless belts or endless platforms arranged side by side at the same horizontal level and traveling in opposite directions at higher speed than the trains of transportation 75 units, as stated. Cooperating with these high speed platforms are means for transversely moving the unit from one of said belts or platforms to the other. Referring to Figs. 1, 2, 11 and 12, an endless belt 80 is arranged longitudinally and horizontally in alignment with the end of the loaded train, which would be the bottom train in Figs. 1 and 12, and the left-hand train in Fig. 11. This belt and the cooperating belt 85 80 are preferably built of parallel metal slats, and are mounted, respectively, upon endless sprocket chains 81, running on sprocket wheels 82 (shown only for belt 89). The sprocket wheels for belt 80 are 90 mounted upon a shaft 84. As embodied, belt or platform 89 is driven from the drive for belt 80. Shaft 84 is shown driven from motor 25 through an idler 85, which idler meshes with the gear 27 and also with a 95 gear 86 fixed on shaft 84. Shaft 84 has fixed thereto a gear 87 meshing with a gear 88, which latter gear is fixed on shaft 83, which gives the requisite difference in direction for the belts 80 and 89. The shaft 100 83 thus drives the belt 89, which is in longitudinal and horizontal alignment with the empty or returning train of transportation units, shown at the top in Figs. 1 and 12, and at the right hand in Fig. 11. Suitable 105 idler sprocket wheels, shafts, bearings, etc., are also provided for supporting and guiding the belts 80 and 89 similar to those shown at the right-hand end of Fig. 11.

Referring to the means cooperating with 110 the high speed belts or endless platforms for shifting the units from one apron to the other and thereby bringing the successive transportation units from alignment with one train into alignment with the other train and for reversing the direction of travel and for speeding each unit up so that it will join the tail of the other train, the embodied form thereof comprises a 115 buffer rail 90 which engages the discon- 120

100

105

110

115

120

125

130

ected unit and shifts it across from belt 80 to belt 89. Rail 90 is mounted upon rods 91 and 92, which rods are reciprocably supported in beveled apertures 93 in supporting posts 94 and 95. At their opposite ends, rods 91 and 92 in said embodied form, are pivotally connected, respectively, to endless chains 96 and 97. The chains are suitably driven and controlled by a stop motion, which stop motion in turn is controlled by the advancing transportation unit, whereby the chains make one complete cycle of travel, and the buffer bar 90 one complete reciprocation. That is, bar 90 is moved from the solid to the dotted line positions in Figs. 11 and 12 and back again, thereby pushing the transportation unit from the apron 80 to the apron 89, and returning to position to act upon the next advancing transportation unit. A bridge piece 98 is interposed between the two aprons upon which the wheels or rollers 13 and 14 slide across from one apron to the other.

Referring to the driving means for the actuating chains 96 and 97 for the buffer bar 90, chain 96 runs over sprocket wheels 99 and 100. Fixed on the shaft of sprocket wheel 100 is a gear 102, with which meshes a gear 103, which gear is fixed on a shaft 104, mounted in suitable bearings 105 and 106. Fixed also to said shaft 104 is a gear 107, with which gear meshes a gear 108 fixed upon the shaft of a sprocket wheel 110. Sprocket chain 97 runs over sprocket wheel 110 and also over a sprocket wheel 111.

In the embodied form of the cooperating means for effecting a single cycle of movement of the buffer bar 90, there is fixed on shaft 84 a bevel gear 112, which meshes with a bevel gear 113, which latter gear is sleeved loosely upon a shaft 104. Fixed to gear 113 is a clutch member 114. A cooperating clutch member 115 is splined to shaft 104 to rotate therewith but is slidable therealong. The clutch member 115 is provided with suitable actuating means, comprising as embodied an annular groove 116 therein with which groove engages pins 117 carried upon a yoke lever 118, which lever is pivoted at 119.

Means are provided controlled by the advancing unit to throw in the clutch 114, 115 and cooperating therewith are means actuated by the chains 96 and 97 reaching the end of one complete rotation or cycle for again throwing out the clutch. In the embodied form thereof, a lever 120 is arranged in the path of travel of the detached transportation unit, which is rapidly approaching upon the belt 80, the lever being thereby actuated to throw electric switch 121, which through circuit 122 energizes a solenoid 123, the core 124 of which is pivotally connected by a rod 125 to the clutch-controlling lever 118. A spring 126 works against the sole-

noid to throw out the clutch. The buffer bar 90 is suitably utilized for the purpose of throwing the lever 121 so as to de-energize the solenoid 123 and throw out the clutch 114, 115, at the end of one complete cycle of movement or rotation. For this purpose (see Fig. 19), switch lever 121 has its end rounded, as shown at 130, and is provided with a one-way pivoted joint 131, with a cooperating spring 132. Thus as the buffer bar 90 passes the switch lever in the direction of the arrow in Fig. 19, the upper end of the lever snaps against the spring and the lever is not moved. As the buffer bar 90 comes back in the opposite direction, it engages switch lever 121, now in the dotted line position of Fig. 19, and throws it back to the full line position, thereby opening the solenoid circuit 122, de-energizing the solenoid, and the clutch 114, 115 is thereby opened. The buffer bar will thus have one reciprocation for each unit which is detached, the unit being thereby transferred from apron 80 to apron 89.

The transferred unit is positioned transversely on apron 89, to which it has been transferred, by the stop 135 which brings it in line with the return track, and when it has been speeded up and forwarded to the end of the departing train of units, its wheels 13 and 14 are received and exactly aligned by the flaring ends 136 and 137 of the outgoing tracks 15 and 16 (Fig. 1). This insures each transferred unit coming back in ample time, and being properly positioned or aligned, and attaching itself to the tail of the last previous departing unit.

In Figs. 14 and 15 are shown, more or less diagrammatically, a junction of two cooperating transporting systems, the trains of one system discharging their transported material into the other system. The general description already given will apply to the mechanism shown in these figures, the direction of travel of the various trains being indicated by the arrows.

In a general system of this kind, both the trains of one system, traveling in both directions, which system may be termed the supplying system, may be employed for transporting material and a plurality of such supplying systems may empty their transported material into a single receiving or final system. Thus only the final or receiving system, having one train of units which discharges into the railway cars will have the empty returning train. That is, referring to Fig. 14 trains 140 and 141 traveling in opposite directions and cooperating together, so far as the shifting of units at the ends of their path of travel is concerned, would each transport the loose material, such as coal, to the receiving or final transporting system, each of the two trains 140 and 141 transporting the material from

opposite directions, and both in the present embodiment discharging the transported material into the train 143 of the cooperating pair or system of trains 143 and 144.

5 Fig. 16 is a diagrammatic showing of any two cooperating trains, which at their two ends shift units from one to the other, irrespective of whether the trains discharge their material at or near the ends of their 10 path of travel, or at some substantially central or intermediate point, as shown in Figs. 14 and 15, and irrespective of whether both trains convey or transport material or whether one train only does so, and the other 15 train merely returns the empty units.

The arrows in Fig. 16 indicate the endless travel of the units and of the trains with their constantly changing succession of units. The switching devices at each end 20 of the tracks are designated generally as 138 and 139, and may be like those shown in Figs. 1, 11 and 12, and already described. The general arrangement of Fig. 16 may be regarded as applied to the trains shown in 25 the other figures, such as Figs. 14, 15, 17 and 18. Such an arrangement maintains a solid train of transporting units traveling in each direction for each system or pair of trains, whatever may be the relation of various 30 systems to each other.

Means are provided by the invention, in accordance with one of its features, for unloading the transported material from one train to another, and usually from a train 35 of one system or pair to a train of another system or pair, and as embodied a chute 142 is employed for this purpose, (Figs. 14 and 15), which may be similar in construction and operation to the chute 70 shown in Figs. 40 9 and 10. The cooperating conveying means, such as the flight conveyor 74, may also be employed if found desirable or necessary. The conveyor 142 transfers the material from train 140 to train 143.

45 To insure the deposit of the transferred material in train 143, a hopper 145 is preferably employed to receive the material from the chute 142 and direct it into the units of train 143. A chute 146 and hopper 147 are also employed for transferring the transported material from train 141 to train 143. In the embodiment of Figs. 14 and 15, train 140 comes loaded from the right, and train 141 comes loaded from the left, both 50 discharging into train 143, while train 144 returns the empty units for train 143; trains 140 and 141 exchanging their units at both termini, as shown in Fig. 16, and trains 143 and 144 cooperating in like manner.

60 In Fig. 17 the mechanism and arrangement of Figs. 14 and 15 are shown applied to a mine worked on the room and entry system, such showing being exemplary and not restrictive in character. In connection therewith are shown transporting mecha-

nism for carrying the coal from the room faces and depositing it in the trains of transportation units. The transportation means shown in the rooms, in more or less diagrammatic form, may be substantially 70 the same as that shown in my copending application S. N. 352,928, filed January 21, 1920.

Fig. 17 shows a practical coal mine installation, wherein the coal from rooms 147 and 148 are conveyed from the room faces in continuous streams, as rapidly as it is mined or dislodged, by the respective transportation devices 149 and 150, which discharge the coal into the train of units 151, 80 which latter may be regarded as corresponding to the train 141 of Figs. 14 and 15.

The cross entries 162 and 163 are preferably directly in line with each other on opposite sides of the main entry 164, whereby 85 one set of unit switching devices at the face or inner end of each entry will do for the transporting systems of both entries 162 and 163. These are not shown in Fig. 17 but will be understood by reference to Figs. 16 and 18. By placing a switching mechanism upon the other side of the main entry from a cross entry, it could be operated singly, that is, without the aligned cross entry.

In entry 163 the rooms 152 and 153 are shown supplied with coal transporting mechanism 154 and 155, respectively, which both discharge into the train of units 156, which may be regarded as corresponding 100 to the train 140 of Figs. 14 and 15.

Discharging devices 157 and 158 are shown discharging the coal from trains 151 and 156, respectively, into train 159 in the main entry 164, and these may be regarded 105 as corresponding to the chutes 142 and 146 of Figs. 14 and 15, already described. The cooperating trains or pair of units 159 and 160 in the main entry 164 may be regarded as corresponding to the trains 143 and 144 110 of Figs. 14 and 15, and need not be described in greater detail.

In this arrangement of Fig. 17, and referring also to Figs. 14, 15 and 16 therewith, the material is transported as quickly as 115 mined, from the rooms to the entry, and is immediately transported in both directions by the two cooperating transportation trains which receive the coal from the room transporting devices in the cross entries at each 120 side of the main entry, and is transported along the main entry without the handling of cars, the waiting of cars or trains of cars on each other, and without one room or entry waiting on the other.

125 In Fig. 18 is shown diagrammatically a substantially complete mining system, so far as the main essentials are concerned, with reference numerals applied thereto as in the preceding figures and description, 130

with a plurality of cross-entries at either side of a main entry, having their respective rooms at either side of the main entry all "working", that is being operated or supplying coal. The transporting train, or rather pair of cooperating trains, for two cross entries in alinement at either side of the main entry is practically a unit as in Fig. 17, having one unit transferring mechanism 138 at one end of one cross entry and a unit transferring mechanism 139 at the end of the other cross entry. Each train of the pair conveys coal from the rooms therewith to the train in the main entry, substantially in the manner described in connection with Figs. 14 and 15. The cross entries are not essentially arranged in alinement across the main entry, but this is an efficient and economical system of working.

It will be noted also that any member of cross entries up to the full carrying capacity of the transporting train of the main entry may be simultaneously worked, and that all the rooms and entries may be simultaneously operated without waiting for, or interference from, the others, and without delays resulting from each other, as already described.

In Fig. 18 also is shown mechanism for discharging the coal from the main entry transportation system directly into a train of railway cars on a siding. A discharge mechanism 165, which may be generally similar to that shown in Figs. 9 and 10, may be employed, discharging into a gravity chute 166, or other suitable device, which in turn discharges into the cars 167 on the railway siding 168.

It will be understood that changes may be made from the mechanisms, constructions and arrangements shown and described without departing from the principles of the invention and without sacrificing its chief advantages.

What I claim is:—

1. A transporting mechanism for loose material in bulk including in combination a plurality of concatenated transporting units, a trackway along which they travel, another plurality of concatenated transporting units, a trackway along which they travel in the opposite direction, and automatically operating means at the ends of the trackway for shifting the end unit transversely of itself from the coming units to the going units.

2. A transporting mechanism for loose material in bulk including in combination a plurality of transporting units connected together at their ends in a longitudinal series, a trackway along which they travel, a plurality of transporting units connected together at their ends in longitudinal series, a trackway along which they travel in the opposite direction, means for detaching one

unit at a time from one series and attaching it to the series traveling in the opposite direction.

3. A transporting mechanism for loose material in bulk including in combination 70 a plurality of concatenated transporting units, a trackway along which they travel, another plurality of concatenated transporting units, a trackway along which they travel in the opposite direction, and means 75 at the ends of the trackway for detaching and shifting the end unit from the coming units to the going units, and means for removing the material from a transporting unit before it is so shifted. 80

4. A transporting mechanism for loose material in bulk including in combination a plurality of concatenated transporting units, a trackway along which they travel, another plurality of concatenated transporting units, a trackway along which they travel, in the opposite direction, and means 85 at the ends of the trackway for shifting the end unit from the coming units to the going units, and means for elevating and removing 90 the material from and over the transporting unit before it is so shifted.

5. A transporting mechanism for loose material in bulk including in combination 95 a plurality of transporting units having bottoms and sides and open at both ends, a trackway along which they travel in connected series, another connected series of similar units, a trackway along which they travel in the opposite direction, and means 100 for transferring successively the head unit from one series into connected relation with the tail of the other series. 105

6. A transporting mechanism for loose material in bulk including in combination 105 a plurality of transporting units having bottoms and sides and open at both ends, a trackway along which they travel in connected series, another connected series of similar units, a trackway along which they travel in the opposite direction, and means 110 for transferring successively the head unit from one series into connected relation with the tail of the other series, and means for detaching a unit from the head of one series 115 and attaching it to the tail of the other series.

7. A transporting mechanism for loose material in bulk including in combination 120 a plurality of transporting units having bottoms and sides and open at both ends, a trackway along which they travel in connected series, another connected series of similar units, a trackway along which they travel in the opposite direction, and means 125 for transferring successively the head unit from one series into connected relation with the tail of the other series, and means for removing the loose material from a unit previous to its transfer. 130

8. A transporting mechanism for loose material in bulk including in combination a plurality of transporting units having bottoms and sides and open one into another at both ends, a trackway along which they travel in connected series, another connected series of similar units, a trackway along which they travel in the opposite direction, and means for transferring successively the head unit from one series into connected relation with the tail of the other series, and means for elevating and removing the loose material from and over a unit previous to its transfer.
- 15 9. A transporting mechanism for loose material in bulk including in combination a plurality of concatenated transporting units opening one into another, a trackway along which they travel, another plurality of concatenated transporting units, a trackway along which they travel in the opposite direction, and means at the ends of the trackway for shifting the end unit from the coming units to the going units, and means for removing the material from a transporting unit comprising an inclined chute within the passing conveyor units and discharging laterally over the side thereof.
- 30 10. A transporting mechanism for loose material in bulk including in combination a plurality of transporting units connected together at their ends and opening one into another in a longitudinal series, a trackway along which they travel, a plurality of transporting units connected together at their ends in longitudinal series, a trackway along which they travel in the opposite direction, means for detaching one unit at a time from one series and attaching it to the series traveling in the opposite direction, and means for removing the material from a transporting unit comprising an inclined chute within the passing conveyor units and discharging laterally over the side thereof.
- 45 11. A transporting mechanism for loose material in bulk including in combination a plurality of transporting units having bottoms and sides and open one into another at both ends, a trackway along which they travel in connected series, another connected series of similar units, a trackway along which they travel in the opposite direction, and means for transferring successively the head unit from one series into connected relation with the tail of the other series, and means for removing the material from a transporting unit comprising an inclined chute within the passing conveyor units and discharging laterally over the side thereof.
- 60 12. A transporting mechanism for loose material in bulk including in combination two parallel trackways, a plurality of concatenated transportation units and means for traveling them along the tracks in two trains in different directions, two high speed conveying means side by side at the end of the trackways, and means for shifting a unit from one of said high speed conveying means to the other.
13. A transporting mechanism for loose material in bulk including in combination two parallel trackways, a plurality of concatenated transportation units and means for traveling them along the tracks in two trains in different directions, two high speed conveying means side by side at the end of the trackways, and means for detaching a unit from the head of the advancing train and delivering it to one of said high speed conveying means.
14. A transporting mechanism for loose material in bulk including in combination two parallel trackways, a plurality of concatenated transportation units and means for traveling them along the tracks in two trains in different directions, two high speed conveying means side by side at the end of the trackways, and means for detaching a unit from the head of the advancing train and delivering it to one of said high speed conveying means, and means for transferring said unit from said high speed conveying means to the other high speed conveying means to bring it to the tail of the departing train.
15. A transporting mechanism for loose material in bulk including in combination two parallel trackways, a plurality of concatenated transportation units and means for traveling them along the tracks in two trains in opposite directions, two parallel trackways transversely passing the first-named trackways, a plurality of concatenated transportation units and means for traveling them along the tracks in two trains in opposite directions, and means for transferring material from one train to another.
16. A transporting mechanism for loose material in bulk including in combination two parallel trackways, a plurality of concatenated transportation units and means for traveling them along the tracks in two trains in opposite directions, two parallel trackways transversely passing the first-named trackways, a plurality of concatenated transportation units and means for traveling them along the tracks in two trains in opposite directions, and means for transferring material from one train to another while they are so traveling.
17. A transporting mechanism for loose material in bulk including in combination two parallel trackways, a plurality of concatenated transportation units and means for traveling them along the tracks in two trains in opposite directions, means for automatically transferring a unit from one of said trains to another, two parallel trackways extending transversely past the first-named trackways, a plurality of concatenated trans-

portation units and means for traveling them along the tracks in two trains in opposite directions, and means for transferring material from one train to another train on a transversely extending trackway.

18. A transporting mechanism for loose material in bulk including in combination two parallel trackways, a plurality of concatenated transportation units and means for traveling them along the tracks in two trains in opposite directions, two parallel trackways extending transversely past the first-named trackways, a plurality of concatenated transportation units and means for traveling them along the tracks in two trains in opposite directions, means for automatically transferring a unit from one of said trains to another, and means for transferring material from one train to another train on a transversely extending trackway while they are so traveling.

19. A transporting mechanism for loose material in bulk including in combination two parallel trackways, a plurality of concatenated transportation units, the units being open at both ends, and means for traveling them along the trackways in two trains in opposite directions, means for automatically transferring a unit from one of said trains to another two parallel trackways extending transversely past the first-named trackways, a plurality of concatenated transportation units means for traveling them along the trackways in two trains in opposite directions, means for automatically transferring a unit from one of said trains to another and means for transferring material from one train to another.

20. A transporting mechanism for loose material in bulk including in combination two parallel trackways, a plurality of concatenated transportation units, the units being open at both ends, and means for traveling them along the trackways in two trains in opposite directions, two parallel trackways extending transversely past the first-named trackways, a plurality of concatenated transportation units means for traveling them along the trackways in two trains in opposite directions, and means for transferring material from one train to another including an upwardly inclined chute within the passing units of one train to elevate and unload the material therefrom and discharging into another of said trains.

21. A transporting mechanism for loose material in bulk including in combination two parallel trackways, a plurality of concatenated transportation units, the units being open at both ends, and means for traveling them along the trackways in two trains in opposite directions, two parallel trackways extending transversely past the first-named trackways, a plurality of concatenated transportation units means for traveling them along the trackways in two trains in

traveling them along the trackways in two trains in opposite directions, and means for transferring material from one train to another, including an upwardly and outwardly inclined chute within the passing units of one train to unload the material therefrom and discharging into one of said transversely passing trains.

22. A transporting mechanism for loose material in bulk including in combination two parallel trackways, a plurality of concatenated transportation units means for traveling them along the trackways in two trains in opposite directions, two parallel trackways extending transversely past the first-named trackways, a plurality of concatenated transportation units means for traveling them along the trackways in two trains in opposite directions, means for automatically shifting a unit from one of said trains to another, and means for transferring material from a plurality of said trains into another of the trains.

23. A transporting mechanism for loose material in bulk including in combination two parallel trackways, a plurality of concatenated transportation units means for traveling them along the trackways in two trains in opposite directions, two parallel trackways transversely passing the first-named trackways, a plurality of concatenated transportation units means for traveling them along the trackways in two trains in opposite directions, and means for simultaneously transferring material from a plurality of said trains into another of the trains while they are all so traveling.

24. A transporting mechanism for loose material in bulk including in combination two parallel trackways, a plurality of concatenated transportation units, the units being open at both ends, and means for traveling them along the trackways in two trains in opposite directions, two parallel trackways extending transversely past the first-named trackways, a plurality of concatenated transportation units means for traveling them along the trackways in two trains in opposite directions, and means for transferring material from one train to another, including inclined chutes within the passing units of each of a plurality of said trains to unload the material therefrom, said chutes discharging into another of said trains.

25. A transporting mechanism for loose material in bulk including in combination two parallel trackways, a plurality of concatenated transportation units, the units being open at both ends, and means for traveling them along the trackways in two trains in opposite directions, two parallel trackways extending transversely past the first-named trackways, a plurality of concatenated transportation units means for traveling them along the trackways in two trains in

- opposite directions, and means for transferring material from one train to another, including an inclined chute within the passing units of each of the trains on one pair of said parallel trackways to unload the material therefrom, said chutes discharging into one of the trains on a transversely extending trackway. 5
26. A transporting mechanism for loose material in bulk including in combination two parallel trackways, a plurality of concatenated transportation units means for traveling them along the trackways in two trains in opposite directions, two parallel trackways transversely passing the first-named trackways, a plurality of concatenated transportation units, means for traveling them along the trackways in two trains in opposite directions, and means for transferring material from one train to another, and means automatically transferring units successively from the head of one train to the tail of the other on the same pair of trackways. 10
27. A transporting mechanism for loose material in bulk including in combination two parallel trackways, a plurality of concatenated transportation units means for traveling them along the trackways in two trains in opposite directions, two parallel trackways transversely passing the first-named trackways, a plurality of concatenated transportation units means for traveling them along the trackways in two trains in opposite directions, and means for transferring material from one train to another, and means automatically transferring units successively from the head of one train to the tail of the other on each pair of trackways. 15
28. A transporting mechanism for loose material in bulk including in combination two parallel trackways, a plurality of concatenated transportation units, the units being open at both ends, and means for traveling them along the trackways in two trains in opposite directions, two parallel trackways transversely passing the first-named trackways, a plurality of concatenated transportation units means for traveling them along the trackways in two trains in opposite directions, means for transferring material from one train to another, an inclined chute within the passing units of each of the trains on one pair of said parallel trackways to unload the material therefrom, said chutes discharging into one of the trains on a transversely passing trackway, and means automatically transferring units successively from the head of one train to the tail of the other on each pair of trackways. 20
29. A transporting mechanism for loose material in bulk including in combination two parallel trackways, a plurality of concatenated transportation units, the units being open at both ends, and means for traveling them along the trackways in two trains in opposite directions, two parallel trackways transversely passing the first-named trackways, a plurality of concatenated transportation units means for traveling them along the trackways in two trains in opposite directions, and means for transferring material from one train to another, and means automatically transferring units successively from the head of one train to the tail of the other on the same pair of trackways. 25
30. A transporting mechanism for loose material in bulk including in combination two parallel trackways, a plurality of concatenated transportation units, the units being open at both ends, and means for traveling them along the trackways in two trains in opposite directions, two parallel trackways transversely passing the first-named trackways, a plurality of concatenated transportation units means for traveling them along the trackways in two trains in opposite directions, means for transferring material from one train to another, an inclined chute within the passing units of one train to unload the material therefrom and discharging into another of said trains, and means automatically transferring units successively from the head of one train to the tail of the other on the same pair of trackways. 30
31. A transporting mechanism for loose material in bulk including in combination two parallel trackways, a plurality of concatenated transportation units, the units being open at both ends, and means for traveling them along the trackways in two trains in opposite directions, two parallel trackways transversely passing the first-named trackways, a plurality of concatenated transportation units means for traveling them along the trackways in two trains in opposite directions, means for transferring material from one train to another, an inclined chute within the passing units of one train to unload the material therefrom and discharging into another of said trains, and means automatically transferring units successively from the head of one train to the tail of the other on each pair of trackways. 35
32. A mine transportation system operating in a main entry and in a cross entry extending transversely to the main entry including in combination a continuous train of concatenated transportation units, means for traveling them along the main entry, and a train of concatenated transportation units, means for traveling them along the cross entry and means for discharging coal into the train in the main entry from the train in the cross entry while the trains are in motion. 40
33. A mine transportation system oper- 45

- ating in a main entry and in a cross entry extending transversely to the main entry including in combination a continuous train of concatenated transportation units opening one into another, means for traveling them along the main entry, and a train of concatenated detachable transportation units opening into one another, means for traveling them along the cross entry and means for discharging coal into the train in the main entry while the trains are in motion. 34. A mine transportation system operating in a main entry and in a cross entry extending transversely to the main entry including in combination a continuous train of concatenated transportation units opening one into another, means for traveling them along the main entry, and a train of concatenated transportation units opening into one another, means for traveling them along the cross entry and means for discharging coal into the train in the main entry while the trains are in motion and coal transportation devices discharging coal from a plurality of workings into the moving train in the cross entry. 35. A mine transportation system operating in a main entry and in a cross entry extending transversely to the main entry including in combination a pair of continuous trains of concatenated transportation units, means for traveling them along the main entry, a pair of continuous trains of concatenated transportation units, means for traveling them along two cross entries at either side of the main entry and across the main entry, and means for transferring the coal from the cross entry trains to the outgoing main entry train. 36. A mine transportation system operating in a main entry and in a cross entry extending transversely to the main entry including in combination a pair of continuous trains of concatenated transportation units opening one into another, means for traveling them along the main entry, a pair of continuous trains of concatenated transportation units opening one into another, means for traveling them along two cross entries at either side of the main entry and across the main entry, and means for transferring the coal from the cross entry trains to the outgoing main entry train while the trains are traveling. 37. A mine transportation system operating in a main entry and in a cross entry extending transversely to the main entry including in combination a pair of continuous trains of concatenated transportation units opening one into another, means for traveling them along the main entry, a pair of continuous trains of concatenated transportation units opening one into another, means for traveling them along two cross entries at each side of the main entry and across the main entry, and means for transferring the coal from the cross entry trains to the outgoing main entry train while the trains are traveling. 38. A transporting mechanism for loose material in bulk including in combination a plurality of concatenated units, each unit having two sides and a bottom, the units together forming an open longitudinal carrier, and an upwardly inclined chute with its bottom end within and close to the bottom of the units, and means for traveling the units past the chute, means for attaching the units to, and detaching them from, each other, and means for automatically operating said attaching and detaching means. 39. A transporting mechanism for loose material in bulk including in combination a plurality of concatenated units, each unit having two sides and a bottom, the units together forming an open longitudinal carrier, and an upwardly inclined chute with its bottom end within and close to the bottom of the units and its top end directed outwardly to one side of the units, and means for traveling the units past the chute, means for attaching the units to, and detaching them from, each other, and means for automatically operating said attaching and detaching means. 40. A transporting mechanism for loose material in bulk including in combination a plurality of concatenated units, each unit having two sides and a bottom, the units together forming an open longitudinal carrier, and an upwardly inclined chute with its bottom end within and close to the bottom of the units, an upwardly traveling conveyor within the chute, and means for traveling the units past the chute, means for attaching the units to, and detaching them from, each other, and means for automatically operating said attaching and detaching means. 41. A transporting mechanism for loose material in bulk including in combination a plurality of concatenated units, the units having bottoms and sides, but being open at the ends and connecting one with another, a trackway, and means for traveling the units along the trackway, means for attaching the units to, and detaching them from, each other, and means for automatically operating said attaching and detaching means. 42. A transporting mechanism for loose material in bulk including in combination a plurality of concatenated units, the units having bottoms and sides, but being open at the ends and connecting one with another, wheels upon which the units are mounted,

a trackway, and means for traveling the units along the trackway, means for attaching the units to, and detaching them from, each other, and means for automatically operating said attaching and detaching means.

43. A transporting mechanism for loose material in bulk including in combination a plurality of concatenated units, the units having bottoms and sides, but being open at the ends and connecting one with another, a trackway, means for traveling the units along the trackway, a second trackway parallel to the first-mentioned trackway, and a plurality of concatenated units thereon, means for traveling the units along the trackway in the opposite direction, and means operating automatically on the arrival of a unit at a given place for shifting a unit from one trackway to another.

44. A transporting mechanism for loose material in bulk including in combination a plurality of concatenated units, the units having bottoms and sides, but being open at the ends and connecting one with another, a trackway, means for traveling the units along the trackway, a second trackway parallel to the first-mentioned trackway, and a plurality of concatenated units thereon, means for traveling the units along the trackway in the opposite direction, and means operating automatically for shifting transversely to itself a unit from one trackway to another.

45. A transporting mechanism for loose material in bulk including in combination a plurality of concatenated units, the units having bottoms and sides, but being open at the ends and connecting one with another, a trackway, means for traveling the units along the trackway, a second trackway parallel to the first-mentioned trackway, and a plurality of concatenated units thereon, means for traveling the units along the trackway in the opposite direction, and means for shifting a unit from one trackway to another and connecting it to the units traveling in the opposite direction upon said other trackway.

46. A transporting mechanism for loose material in bulk including in combination a plurality of concatenated units, the units having bottoms and sides, but being open at the ends and connecting one with another, a trackway, means for traveling the units along the trackway, a second trackway parallel to the first-mentioned trackway, and a plurality of concatenated units thereon, means for traveling the units along the trackway in the opposite direction, and means operating automatically for shifting a unit from one trackway to another and connecting it to the units traveling in the opposite direction upon said other trackway.

47. A transporting mechanism for loose

material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, and means for transferring successive units traveling in the opposite direction from one trackway to another.

48. A transporting mechanism for loose material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, and means for transferring successive units from one trackway to another and for changing the direction of travel of the unit during said transference.

49. A transporting mechanism for loose material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, and automatically operating means for transferring successive units from one trackway to another and changing the direction of its travel during the transfer.

50. A transporting mechanism for loose material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, and automatically operating means for transferring successive units from one trackway to another and for changing the direction of travel of the unit during said transference.

51. A transporting mechanism for loose material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, a traveling platform at the end of one trackway and traveling in the same direction therewith, to receive the transportation units, a traveling platform at the end of the other trackway and traveling in the same

direction therewith, and means for transferring a transportation unit sidewise from one of said platforms to the other.

52. A transporting mechanism for loose material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, a traveling platform at the end of one trackway and traveling in the same direction therewith, to receive the transportation units, a traveling platform at the end of the other trackway and traveling in the same direction therewith, and automatically operating means for transferring a transportation unit sidewise from one of said platforms to the other.

53. A transporting mechanism for loose material in bulk including in combination a trackway, a plurality of wheeled transportation units thereon, a parallel trackway, a plurality of wheeled transportation units thereon, means for traveling the wheeled units along one trackway in one direction, means for traveling the wheeled units along the other trackway in the opposite direction, a traveling platform at the end of one trackway and traveling in the same direction therewith, to receive the transportation units, a traveling platform at the end of the other trackway and traveling in the same direction therewith, and means called into operation by a transportation unit passing from a trackway to a traveling platform for transferring the transportation unit sideways from one of said platforms to the other.

54. A transporting mechanism for loose material in bulk including in combination a trackway, a plurality of wheeled transportation units thereon, a parallel trackway, a plurality of wheeled transportation units thereon, means for connecting said units in a series, means for traveling the wheeled units along one trackway in one direction, means for traveling the wheeled units along the other trackway in the opposite direction, and means for disconnecting a unit from the series on one trackway, transferring it to the other trackway and connecting it to the units on said other trackway.

55. A transporting mechanism for loose material in bulk including in combination a trackway, a plurality of wheeled transportation units thereon, a parallel trackway, a plurality of wheeled transportation units thereon, means for connecting said units in a series, means for traveling the wheeled units along one trackway in one direction, means for traveling the wheeled units along the other trackway in the opposite direction, and automatically operating means for dis-

connecting a unit from the series on one trackway, transferring it to the other trackway and connecting it to the units on said other trackway.

56. A transporting mechanism for loose material in bulk including in combination a trackway, a plurality of wheeled transportation units thereon, a parallel trackway, a plurality of wheeled transportation units thereon, means for connecting said units in a series, means for traveling the wheeled units along one trackway in one direction, means for traveling the wheeled units along the other trackway in the opposite direction, a traveling platform at the end of one trackway and traveling in the same direction therewith, to receive the transportation units, a traveling platform at the end of the other trackway and traveling in the same direction therewith, and means for disconnecting a unit from the series on one trackway as it enters upon the corresponding platform and for transferring it from said platform to the other platform and for connecting it to the series of units upon the other track.

57. A transporting mechanism for loose material in bulk including in combination a trackway, a plurality of wheeled transportation units thereon, a parallel trackway, a plurality of wheeled transportation units thereon, means for connecting said units in a series, means for traveling the wheeled units along one trackway in one direction, means for traveling the wheeled units along the other trackway in the opposite direction, a traveling platform at the end of one trackway and traveling in the same direction therewith, to receive the transportation units, a traveling platform at the end of the other trackway and traveling in the same direction therewith, and automatically operating means for disconnecting a unit from the series on one trackway as it enters upon the corresponding platform and for transferring it from said platform to the other platform and for connecting it to the series of units upon the other track.

58. A transporting mechanism for loose material in bulk including in combination a trackway, a plurality of wheeled transportation units thereon, a parallel trackway, a plurality of wheeled transportation units thereon, means for connecting said units in a series, means for traveling the wheeled units along one trackway in one direction, means for traveling the wheeled units along the other trackway in the opposite direction, a traveling platform at the end of one trackway and traveling in the same direction therewith, to receive the transportation units, a traveling platform at the end of the other trackway and traveling in the same direction therewith, and means called into action by a transportation unit reaching the

end of a trackway for disconnecting a unit
from the series on one trackway as it enters
upon the corresponding platform and for
transferring it from said platform to the
5 other platform and for connecting it to the
series of units upon the other track.

In testimony whereof, I have signed my

name to this specification, in the presence
of two subscribing witnesses.

KENNETH DAVIS.
